BIRD FEEDER

Arthur W. Blazier, Montclair, N. J.

Application May 11, 1950, Serial No. 9,884

Term of patent 14 years

(Cl. D31—2)

To all whom it may concern:

Be it known that I, Arthur W. Blazier, a citizen of the United States, residing at Montclair, in the county of Essex and State of New Jersey, have invented a new, original, and ornamental Design for a Bird Feeder, of which the following is a specification, reference being had to the accompanying drawings, forming part thereof, in which:

Fig. 1 is a top plan view of a bird feeder, showing my new design;

Fig. 2 is a side elevation; and

Fig. 3 is a bottom plan view.

I claim:

The ornamental design for a bird feeder, substantially as shown.

ARTHUR W. BLAZIER.
